UNITED STATES PATENT OFFICE.

FORREST A. BLACK, OF MARION, INDIANA.

AXLE STRETCHER, STOVER, AND BENDER.

1,236,533.

Specification of Letters Patent. Patented Aug. 14, 1917.

Application filed August 26, 1916. Serial No. 116,947.

To all whom it may concern:

Be it known that I, FORREST A. BLACK, a citizen of the United States, residing in Marion, county of Grant, State of Indiana, have invented certain new and useful Improvements in Axle Stretchers, Stovers, and Benders, of which the following is a specification.

My invention relates to the art of shaping metal articles and particularly to a machine so constructed as to adapt it for use in stretching, shortening, shaping and finishing drop-forged axles.

In the manufacture of motor trucks, automobiles, etc., it is the usual practice to employ drop forged front axles, and sometimes drop forged rear axles. Experience has shown that forgings made from the same die or same set of dies vary somewhat in length, width, etc. To compensate for these variations it has been the practice to correct the fault of dimensions by manual operation, that is, by a gang of men working every one of the several forgings separately, to correct whatever variations may occur, such as straightening, shortening, lengthening, truing to size, etc. It is obvious that such means of correction are very expensive, entailing a finishing operation after the parts have been made in the forging machine.

I intend to rectify these objections by means hereinafter explained. One of the objects of my invention is to provide a machine that will, with one stroke of the plunger, lengthen a forged axle if it be too short, shorten it if it be too long, straighten it, shape the pads for the springs, and bend the central portion of the axle into any desired shape.

Another object is to provide a machine which will stretch or stope any other forgings requiring such attention.

To enable those skilled in the art to more fully understand my invention, attention is directed to the drawings showing the preferred embodiment of my invention, wherein—

Figure 1 is a side elevation of a bulldozer provided with dies necessary to carry out my invention.

Fig. 2 is a plan view of Fig. 1.

Fig. 3 is a horizontal section on line 3—3 of Fig. 1.

Fig. 4 is a section on line 4—4 of Fig. 2.

Fig. 5 is a section on line 5—5 of Fig. 4.

The numeral 10 represents the bulldozer with a reciprocating head 11 operated by

means of a balanced crank 12 connected with the head 11 by the pitman 13. The crank 12 is mounted on the shaft 14, the rotation of which is brought about by any suitable means, not shown.

In the type of bulldozer shown, the head 11 is adapted for reciprocal motion on the slideway 15 on the top portion of the bed 10. The head 11 is provided with the usual vertical face 16, to which are attached portions of my device. These will be fully explained hereinafter.

One of the novel features of my invention is the shape and kind and arrangement of the dies for accomplishing the stretching or stoving of the drop forging to be treated.

Mounted on the upper portion of the bed 10 is a die block 17. This block extends 75 transversely of the bed and is fastened thereto by any suitable means, the fastening means which are shown in my embodiment consisting of bent pins 18 hooked under the edges of the upper portions of the side 80 of the bed 10. As a fixed back stop, I provide the lugs 18^a integral with the bed, and serving to support adjusting bolts 18^b which directly control the die block. Extending lengthwise of this block is a groove 19 85 which is in the form of an inverted T. Connected to the block 17 is the upper die block 20, which has also a T-shaped groove extending throughout its length. The upper die block 20 is hinged or connected to the 90 lower die block 17 by pivoted arms 21, the arm 21 being securely fastened to upper die block 20 and suitably mounted on pin 22 in die block 17.

Referring to Fig. 5, the construction of 95 the dies will be more apparent. Mounted in the groove 19 of the bottom die block 17 are sliding blocks 23 and 24, the block 24 being relatively longer than the block 23. In the end of block 23 I provide a screw threaded 100 aperture 23^a. To coöperate therewith, a screw 25 is mounted in bracket 26, secured to the end of block 17. By this means I am able to adjust or fix the position of the die block 23, the necessity for which will be 105 explained later. The block 24 is freely slideable in the groove 19.

The dies are made in separate pieces; in other words, I use two blocks placed apart for the upper die and two blocks placed 110 apart for the lower dies, the corresponding blocks of the upper and lower dies mating.

Numerals 27 and 28 indicate the lower dies of the preferred form of my invention,

Die 27 I bolt to block 23, as is best seen in Fig. 5. This die is made to extend beyond the inner edge of block 23 and overlies the inner end of block 24, as best shown in Fig. 5. This is to provide a sufficient bearing surface therefor. The die block 28 is fastened to the sliding block 24 and is movable therewith. The upper die is fastened to the sliding block 31, which is mounted in the groove 20^a in the top die block 20. The die blocks are adapted to mate and the die blocks 28 and 30 must be movable in unison. The tongue 28^a connects the dies 28 and 30 for that purpose. The tongue 28^a is attached in any suitable manner to the lower die block 28 and engages the sliding die block 30, in a slot 30^a so that when the upper die is closed against the lower die the tongue 28^a will enter the slot and permit the closing of the upper die block on the lower and allow for movement of the die blocks 28 and 30. The tongue 28 is curved the radius of which curve is the same radius about which the upper die moves, consequently there can be no binding between the tongue 28^a and the sliding die block 30. The sliding block 24 is provided with a longitudinally extending aperture 32 carrying two rollers 33 and 34 vertically mounted therein for horizontal rotation. These rollers are spaced apart and positioned near the end of the slot 32. The reason for this arrangement will be explained later.

Mounted on the head 11 of the bulldozer is a horizontally extending tongue 35, which tongue extends through the aperture 32 between the rollers 33 and 34 in the die block 24. The tongue 35 is wider at its inner end than at its outer end. This will be seen by referring to Fig. 3.

For closing the top die onto the lower die, I provide an arm integral with or attached to the die block 20, which arm is curved as shown in Fig. 4 and has a roller 45 at its end. This arm is adapted to extend below the lower portion of die block 17. The outer end of tongue 35 is provided with a block 37, in which there is mounted for rotation a roller 38, which roller is adapted to bear against the inner portion of the curved arm 36. The rearward or convex side of the arm 36 is provided with a series of counterweights 39 held thereon by means of slide 39^a. Counterweights may be added to or taken from the arm 36, the addition or subtraction of the counterweights depending upon the weight of the dies fastened to the upper die blocks.

The die blocks 27, 28 and the upper die blocks 29 and 30, when mounted for use, are spaced apart as best seen in Fig. 5 and Fig. 2.

Also mounted on the base of the head 11 of the bulldozer is a tongue 40 mounted above the tongue 35 and much shorter in

length. On each side of the tongue 40 are mounted tongues 41 and 42. The purpose of the tongue 40 is to bend into the desired shape the central portion of the axle being treated in this machine. Referring to Fig. 2, it will be seen that I provide at the rear side of the lower die a die 43 having a base shaped to the contour that it is desired to bend the central portion of the axle.

The tongue 40 mounted on the head 11 is formed to the same shape that die block 43 is.

The rear portion of the block 17 is provided with an arcuate slot shown in Fig. 4 and designated by numeral 44 wherein the arm 36 may operate. This provision is made to insure at all times proper fitting or mating movement of the upper die block onto the forging in the lower dies which is to be treated therein.

The operation of the machine is as follows: An axle designated by numeral 46 in Fig. 2 is inserted in the lower die blocks 27 and 28. When lying in this position the axle is gripped at the ends, leaving the middle portion free or open. By means of the screw 25 the block 24 is adjusted to the proper position for the axle, which is in the dies. To accommodate the lengthwise position of the die block 28 to the length of the axle, the block 24 may be moved inwardly or outwardly until the end of the axle fits in the die block 28. Movement of this block will change the position of the rollers 33 and 34 with respect to the tongue 35 attached to the head. When the bulldozer is actuated, the tongue 35 is moved forwardly, bringing the wider portion of the tongue against one of the rollers 33 or 34 mounted in the sliding block 24, and thus moves the sliding block 24 either way. The closing of the upper die block on the lower is accomplished by coöperation between the end of the tongue 35 and the curved arm 36 fastened to the upper die block, this being best seen in Fig. 4. As head 11 carrying the tongue 35 moves forwardly the end of the tongue pushes against the curved arm 36 and forces the upper die block downwardly against the lower die block and against any forging that is held by the dies. As the upper die block is closed against the lower die block it is held there by reason of the engagement of the roller 45 carried by the end of the arm 36 with the upper surface of the tongue 35. This results in the upper die block being held against the lower die block and against any forging that is thereby held while the head 11 completes its forward stroke and during a portion of its rearward stroke. As the end of the arm 35 leaves the roller 45 the counterweights 39 will open the upper die block and return it to its normal vertical position.

If the forging being treated is 130

too long, the block 24 will be in such a position that the roller 33 will be engaged by the side of the tongue 35, thereby drawing inwardly the block 24 or shortening the forging 46. By virtue of the shape of the side of the tongue 35 the forging will be retained in the correct position during the time that the cross head completes its stroke. As the cross head continues to travel, the tongue 40 engages the middle portion of the axle, bending it into the form of the die 43 and the tongue 40. Also, the tongues 41 and 42 engage the portions 48 and 49, which are the spring pads on which the springs rest when the axle is assembled into the motor vehicle.

The moment the cross head 11 starts forward the outer end of the tongue 35 closes the top die onto the axle forging and holds it in position. The movement of the upper die block 30 corresponds to the movement of the lower block 28 when the tongue 35 engages either of the rollers 33 or 34. As the cross head is withdrawn, the upper die block 25 is opened by reason of the action of the counterweights on the withdrawal of the end of the tongue 35 from engagement with the inner portion of the arm 36, so that by the time the cross head has reached its position of rest the dies will be open and all their parts out of engagement one with the other. If the axle forging is too short, then, when placed in position in the dies 27 and 28, the sliding block will be moved 35 sidewise so that the roller 34 will be engaged by the tongue 35, thereby lengthening to the exact length the axle forging 46.

It will be observed that I have furnished means for treating forged axles in such a manner that the finished product will be uniform in length, contour and shape and will have to undergo no great amount of machining. By reason of the fact that the middle portion of the axle is not held in dies, it is possible to lengthen a forging that is too short or shorten a forging that is too long, by reason of the slidability of the lower die blocks and the simultaneous slidability of the corresponding upper die blocks. 45 Also, by reason of the sliding die blocks it is possible to compress the forging so that it will fill completely the die blocks, thereby forming an axle true to shape in every respect. Also, because of the freedom of 50 movement of the middle portion of the axle, it is possible to shape the middle portion as desired.

By an apparatus of this sort it is possible to treat in a similar manner forgings of any kind wherein such treatment is desired. The arrangement of the respective parts will be substantially the same, and the operation of the bulldozer exactly the same. The limit of sidewise movement of the block 24 55 is dependent upon the width of the narrow

and wide portions of the tongue 35, and the point of beginning and ending of the sliding movement is depending upon the sharpness of the wedge-like sides connecting the narrow and the wide portions. Means for 70 moving the upper die blocks 29 and 30 simultaneously with their mating lower blocks 27 and 28 respectively may be hinges or telescopic joints so connected that the movement of the blocks 23 and 24, carrying the 75 dies 27 and 28, may be transferred to the block 31 carrying the dies 29 and 30, whereby any movement of the block 23 or 24 will be brought about in the corresponding block 31. Such means will in no way hamper the 80 closing and opening movements of the upper die member.

I do not limit the scope of my invention to the exact form shown and described, but consider as coming within the spirit of my 85 invention such machines as will lengthen or shorten metal formations by means of expanding or contracting die members, the expansion or contraction of the dies being accomplished or brought about during the 90 operation of stretching, straightening or shortening.

Having fully described my invention, what I desire covered by Letters Patent is:

1. In a bulldozer, the combination of two 95 pairs of dies spaced apart and adapted to grasp and hold the ends of an article, one pair of said dies being freely slidable toward and from said other pair, and a reciprocating plunger coöperating with said slid- 100 able dies to position the same in a predetermined position and consequently to fix the length of the article being treated, substantially as described.

2. In a bulldozer, the combination of two 105 pairs of dies spaced apart and adapted to grasp and hold the ends of an article, one pair of said dies being freely slidable toward and from said other pair, a reciprocating plunger coöperating with said slidable dies 110 to position the same in a predetermined position and consequently to fix the length of the article being substantially treated, the ends of the article being unchanged in shape during such operation, the distortion occurring in the intermediate portion of the article, and means operative subsequent to 115 said length-fixing operation to reshape said intermediate portion, substantially as described.

3. In a machine of the class described, the combination of a set of die blocks, a set of sliding blocks mounted in said die blocks, dies secured to said sliding blocks, the die blocks being adapted to close and the dies to 125 mate, a cross head, a tongue on said cross head adapted to engage said die blocks, said sliding blocks being operable by said tongue into closed and then into open positions, substantially as described.

4. In a machine of the class described, the combination with a frame, of a reciprocating cross head mounted thereon and a set of die blocks mounted transversely of said frame, the blocks being provided with apertures, sliding members mounted in the apertures, dies secured to the sliding members, the dies comprising several parts for the upper die and the same number of parts for the lower die, the several parts of each die being in spaced relation when in active position, a plunger mounted on said cross head for cooperation with the sliding blocks, whereby the same are moved into position for action by the dies, substantially as described.

5. In a machine of the class described, the combination with a frame, of hinged die blocks mounted on said frame transversely thereof, the blocks being provided with longitudinally extending apertures, sliding members mounted in said apertures, upper and lower dies, each die comprising at least two parts, one part fastened to one of said sliding members, coöperative connecting means between corresponding sliding members in upper and lower blocks, whereby same are slid simultaneously, a plunger engaging the sliding members and adapted to close and open the die blocks, also to move the sliding blocks into operative position, and to extend between the parts comprising the upper and lower parts when the plunger is at the end of its stroke, substantially as described.

6. In a stretching and stoving machine, the combination with a frame of a traveling cross head, die blocks mounted on the frame transversely thereof, the blocks being hingedly connected, sliding members engaging said blocks, dies for the upper and lower blocks, each die comprising a plurality of parts, the parts being mounted on the several sliding members, permitting movement of one part with respect to the other part, the cross head provided with a two-part plunger, one part engaging the sliding members and the top die block, whereby the top die block is moved into mating position with the lower block, and the sliding members in both blocks moved into operating position, substantially as described.

7. In a stretching and stoving machine, a combination with a frame of a reciprocating cross head and a set of die blocks mounted on said frame transversely thereof, the die blocks being hinged for operation in a jaw-like manner; the upper die block being provided with an arm extending around and underneath the lower die block, each die block being provided with a series of sliding members, dies formed of several parts mounted on the sliding members, means

connecting the corresponding sliding members of the upper and lower die blocks, whereby simultaneous movement is had, a plunger mounted on the cross head engaging the sliding members of the lower die blocks, said plunger being substantially wedge-like in plan view, rollers mounted on one of the sliding members of the lower die blocks for engagement with said plunger, said plunger also engaging the arm of the upper die blocks, the dies being mounted on the sliding members so as to provide a space between the several parts of each die, whereby to permit stretching or compressing of material held by the die parts, means for operating said plunger operating the sliding members of the lower die blocks and also the top die blocks, substantially as described.

8. A pair of die blocks for forging machine comprising upper and lower blocks, each block provided with a longitudinally extending aperture, separable sliding members inserted in each of said apertures, means connecting the die block to one of said sliding members whereby its position is fixed, dies composed of several parts, the several parts fastened to the sliding members, hinge connections between the corresponding sliding members of the top and bottom die blocks, whereby simultaneous movement thereof is effected, means for closing the die blocks and means for operating the slidables members, substantially as described.

9. In a machine of the class described, the combination of a pair of die blocks fastened in hinged positions, each die block being provided with a longitudinally extending slot, a plurality of sliding members mounted in each of said slots, means whereby at least one of said sliding members may be retained in a fixed position in said slot, the other sliding members being freely slidable, the sliding block being provided with a horizontally disposed slot, rollers mounted in said slot, and dies, the dies for each of the upper and lower die blocks being formed of a plurality of sections, the sections being fastened one to the fixed sliding member and another to the freely slidable sliding member, and being maintained in spaced relation when so fastened, a wedge-shaped tongue engaging the slot in said sliding member whereby sliding movement thereof is effected, adapted also to close the upper die block against the lower after the sliding blocks are moved into active position.

Signed at Marion, Indiana, this 21st day of August, 1916.
